HEAT-SEALED GUSSET POCKET

George Markus, West Orange, N.J., and Martin Siegel, Roslyn, N.Y., assignors to Aristocrat Leather Products, Inc., New York, N.Y., a corporation of New Jersey

Filed Jan. 14, 1960, Ser. No. 2,515

12 Claims. (Cl. 150—38)

This invention relates to wallets or billfolds of the type which are provided with auxiliary gusset pockets.

One of the objects of the present invention is to provide a wallet or billfold, of the above indicated type, made partly or entirely of non-heat-sealable material, for example, leather, which has the gussets of the auxiliary pocket secured to a wall of the wallet or billfold with heat-sealed means.

A further object is to provide a wallet or billfold having an auxiliary gusset pocket made of non-heat-sealable material with the gussets of the pocket secured to the wallet with heat-sealed means, other parts of the wallet being made partly or entirely of material which is also non-heat-sealable.

Another object of this invention is to facilitate the manufacture of wallets of the gusset pocket type by providing a construction which enables the gusset pocket to be attached to the wallet by simple and convenient assembly and securing operations.

Another object is generally to provide a wallet or billfold of the above indicated type having improved means for securing the gussets of the auxiliary pocket to a wall of the billfold, said billfold being made of heat-sealable material or non-heat-sealable material or a combination of both.

The above and other objects, features and advantages of this invention will be fully understood from the following description considered in connection with the accompanying illustrative drawings of the presently preferred embodiment of this invention.

In the drawings:

FIG. 1 is a view of the inner side of a foldable wallet or billfold in its open or unfolded condition;

FIG. 2 is a perspective view of part of the billfold showing the auxiliary gusset pocket in an open and expanded condition;

FIG. 3 is a plan view of a die cut blank of a pocket member in flat condition before it is attached to the billfold;

FIG. 4 is a perspective rear view of part of the billfold, with parts omitted, illustrating an intermediate step in securing the auxiliary gusset pocket to a wall member of the billfold;

FIG. 5 is a view similar to FIG. 4, with portions cut away, showing the gusset pocket secured to the wall member of the billfold;

FIG. 6 is a sectional view taken on line 6—6 of FIG. 2, on a slightly larger scale;

FIG. 7 is a sectional view taken on line 7—7 of FIG. 2, on a slightly larger scale;

FIG. 8 is an exploded perspective view of part of a billfold, in accordance with another embodiment of the invention, illustrating the parts in a disassembled condition;

FIG. 9 is a perspective view similar to FIG. 8 with the parts in an intermediate condition of assembly;

FIG. 10 is a view similar to FIG. 9, with the parts shown in their assembled condition; and

FIG. 11 is a sectional view taken on line 11—11 of FIG. 10.

Referring now to the drawings in detail, the billfold 10 may be of any usual or conventional construction and includes the main bill compartment defined by the outer wall 12 and the inner wall 14 which includes a

2

folded over wall 16, the bills being disposed between said folded over wall 16 and outer wall 12. A conventional compartment 18 is provided between folded over wall 16 and inner wall 14 and part of said inner wall 14 constitutes a front wall member 20 for compartment 18, to which is secured an auxiliary gusset pocket 22 formed from a blank 22A, illustrated in FIG. 3.

In the embodiment of the invention illustrated in FIGS. 1—7, the billfold is made partly of heat-sealable material and partly of non-heat-sealable material, although it will be understood that the billfold may be made entirely of heat-sealable material or material coated with a heat-sealable material. More particularly, the outer wall 12, the gusset pocket 22, and the foldable closure member or flap 24 are made from a non-heat-sealable material, for example leather, which enhances the appearance of the billfold and provides better wearing material for those parts of the billfold subject to excessive wear. The remaining parts of the billfold, including the front wall member 20 of the compartment, are made of heat-sealable material, for example, vinyl sheet plastic material or cloth or paper having on one surface thereof a coating of vinyl plastic or other heat-sealable material. As will be clearly seen hereinafter, the heat sealable surface of wall member 20 is used for securing the pocket 22 to said wall member with heat-sealed means.

As illustrated in FIG. 3, the blank 22A for forming the auxiliary gusset pocket 22 includes the part 26 which constitutes the front wall of the pocket and the foldable parts 30, 32 at each side edge of said front wall to provide the gussets 32 of the pocket, as best shown in FIGS. 2 and 5.

The blank 22A is also provided with the integral end parts 34 which have tongue extensions 36 with end slits 38. It will be understood that the blank 22A is formed in one integral piece, being die cut to the outline illustrated by FIG. 3, or to any other suitable outline according to variations which may be made in the details of the form and construction of the pocket pursuant to the present invention. Flap 24 and front wall 26 of the pocket are preferably provided with companion releasable fasteners, here shown as snap fasteners 40 and 42, for releasably securing said flap 24 in closed position.

The wall member 20 is provided with foldable end portions 44, as best seen in FIGS. 4 and 5, each of said end portions being provided with a slit 46. As shown in FIGS. 2 and 4, to secure the pocket 22 to wall member 20, the lower edge 48 of the front wall 26 of the pocket is secured, by stitching 50, to the lower edge of wall member 20 and the extensions 36 of the pocket are inserted in the slits 46 of end portions 44 and extend in overlapping surface-to-surface contact with said end portions, at the rear surfaces thereof, as shown. The slits 38 provide an interlock for the extensions 36 with the adjacent parts of end portions 44 at the slits 46, which will be readily understood. It will also be noted that the extensions 36 are inserted in said slits 46 at the front of wall member 20 while the end portions 44 are lying in their flat unfolded positions.

The end portions are folded over against the rear surface of wall member 20 so that extensions 36 are disposed between said rear surface and said folded over end portions 44 with the heat-sealable surfaces of said folded over portions facing the rear or main wall 12 of the billfold. If desired, the folded over end portions may be temporarily secured in their folded condition by cementing the front surfaces thereof to the rear surface of wall member 20, which need not be a heat-sealable surface. A sheet of material or wall member 52, which is made of heat-sealable material or has a heat-sealable coated surface, for example a vinyl plastic coating, is superimposed on the heat-sealable surfaces of said folded over end portions 44 and is heat-sealed to said end portions for secur-

ing said end portions in said folded over condition, whereby the extensions 36 are locked in position and the gusset end parts 34 of the pocket are secured to wall member 20, as best seen in FIGS. 5, 6 and 7. The flap 24 of the pocket may be secured to the upper edge of wall member 20, as by stitching 54.

The manner in which the heat-sealing operation is accomplished is believed to be obvious to those skilled in the art. It may be noted that the operation is preferably accomplished while the main walls 12 and 14 and wall 16 are in a flat unfolded condition and a metal plate forming one electrode of the di-electric heat-sealing apparatus is inserted in pocket 22 after the extensions 36 are inserted through the slits 46 of end portions 44. The opposite side of the flat blank is positioned within a shallow metal tray which constitutes the other electrode of the di-electric heat-sealing apparatus so that the parts of the billfold are in position for the heat-sealing operation. A further detailed description of the heat-sealing operation is not considered necessary as it does not, per se, form part of the invention apart from the construction of the gusset pocket 22 and the heat-sealing operation for securing the pocket to wall member 20.

It will be understood, as mentioned above, that billfold 10 may be made entirely of heat-sealable material, for example paper or cloth coated with vinyl plastic. In such case the extensions 36 will not only be locked in position between folded over portions 44 and the rear surface of wall member 20, but also the heat-sealable surfaces of said extensions 36 will be heat-sealed to the heat-sealable surfaces of said folded over portions with which they are in surface contact.

Referring now to FIGS. 8 through 11 of the drawings, there is shown another embodiment of the invention wherein a billfold 10A is made entirely of non-heat-sealable material, for example leather. In FIG. 8, the pocket 22 is shown secured at its lower edge to the front surface of wall member 20, at the lower edge thereof, by stitching 50, as previously described. A sheet of material or wall member 56, having a main portion 58, and foldable end portions 60, provided with slots 62, is adhesively secured to the rear surface of wall member 20 along the front surface of portion 58. The extensions 36 of the gussets are inserted in slots 62, respectively, as best seen in FIG. 9, at the front of wall member 20, and the end portions 60 are folded over so that the heat-sealable surfaces of said end portions 60 are in surface-to-surface contact with the heat-sealable surface of portion 58, as best seen in FIGS. 10 and 11, with extensions 36 being disposed between the confronting heat-sealable surfaces of portion 58 and end portions 60. Said end portions 60 are then heat-sealed to portion 58 whereby extensions 36 are secured to wall member 56 and wall member 20. Thus it will be seen that portion 58 constitutes means heat-sealed to said folded over end portions 60 for retaining said end portions in their folded over condition so that pocket 22 is mounted on wall members 20 and 56 of compartment 18. If desired, an additional wall member 64 may be superimposed on folded wall member 56 and heat-sealed thereto, as shown in FIGS. 10 and 11.

The present application is related to our application Serial No. 811,930 filed May 8, 1959, now Patent No. 2,962,071.

While we have shown and described the preferred embodiment of our invention, it will be understood that the invention may be embodied otherwise than as herein specifically illustrated or described, and that certain changes in the form and arrangement of parts and in the specific manner of practicing the invention may be made without departing from the underlying idea or principles of this invention within the scope of the appended claims.

What we claim is:

1. In a wallet, billfold or the like, a compartment having a wall member, folded over end portions con-

nected to said wall member, each of said end portions having a slit and a surface of heat-sealable material, a pocket member having a front wall and end portions projecting through said slits for attachment of said pocket member to said wall member, and means heat-sealed to said heat-sealable material for securing said folded over end portions in said folded over condition and thereby securing said end portions of said pocket member to said wall member.

5 2. In a wallet, billfold or the like, a compartment having a wall member, folded over end portions connected to said wall member, each of said end portions having a slit and a surface of heat-sealable material, a pocket member having a front wall and end portions 10 projecting through said slits for attachment of said pocket member to said wall member, and means heat-sealed to said heat-sealable material in overlapping surface-to-surface contact therewith for securing said folded over end portions in said folded over condition and thereby securing said end portions of said pocket member to said wall member.

15 3. In a wallet, billfold or the like, a compartment having a wall comprising two wall members in laminated relation, one of said wall members having a surface of 20 heat-sealable material and provided with folded portions having slits, respectively, a pocket member mounted on said wall of the compartment and having portions projecting through said slits respectively, and overlapping the portions of said one wall member adjacent said slits, said 25 folded portions of said one wall member being heat-sealed to said heat-sealable surface of said one wall member for securing said portions of said pocket member in said overlapped relation.

30 4. In a wallet, billfold or the like, a compartment having a wall member of non-heat-sealable material, a sheet of material adhesively secured to said wall member and having a surface of heat-sealable material and folded over end portions provided with slits, respectively, a 35 pocket member having a front wall and end portions projecting through said slits for attachment of said pocket member to said wall member, said folded over end portions being heat-sealed to said sheet of material with said pocket member end portions disposed therebetween for securing the latter to said wall member.

40 5. In a wallet, billfold or the like, a compartment having a wall comprising two wall members in superimposed face-to-face relation and adhesively secured to each other in said superimposed relation, one of said wall members having a surface of heat-sealable material and provided with folded portions having slits, respectively, a pocket member mounted on said wall of the compartment and having portions projecting through said slits, respectively, and overlapped the portions of 45 said one wall member adjacent said slits, said folded portions of said one wall member being heat-sealed to said heat-sealable surface of said one wall member for securing said portions of said pocket member in said overlapped relation.

60 6. In a wallet, billfold or the like, a compartment having a wall member and a gusset-pocket member mounted on said wall member, said gusset-pocket member being made of leather and having gussets terminating in end portions in overlapping relation with portions of 65 said wall member and attached thereto, said wall portions having heat-sealable surfaces, and means heat-sealed to said surfaces of said wall portions for securing said wall portions and said ends of the gussets in said attached and overlapping relation.

70 7. In a wallet, billfold or the like, a compartment having a wall member having a surface of heat-sealable material and having folded over end portions provided with slits, respectively, a pocket member having a front wall and end portions of non-heat-sealable material projecting through said slits for attachment of said pocket member to said wall member, and means heat-sealed to said heat-

sealable material for securing said folded over end portions in said folded over condition and thereby securing said end portions of said pocket member to said wall member.

8. In a wallet, billfold or the like, a compartment having a wall comprising two wall members, one of said wall members having a surface of heat-sealable material and provided with folded portions having slits, respectively, a pocket member mounted on said wall of the compartment and having portions projecting through said slits, respectively, and overlapping the portions of said one wall member adjacent said slits, the other of said wall members having a surface heat-sealed to said folded portions of said one wall member for securing said portions of said one wall member in said folded condition and for securing said portions of said pocket member in said slits and in said overlapped relation.

9. In a wallet, billfold or the like, a compartment having a wall member, folded over end portions connected to said wall member, each of said end portions having a slit and a surface of heat-sealable material, a pocket member having a front wall and end portions projecting through said slits for attachment of said pocket member to said wall member, and means heat-sealed to said heat-sealable material in overlapping surface-to-surface contact therewith for securing said folded over end portions in said folded over condition and thereby securing said end portions of said pocket member to said wall member, said pocket member having integral gussets at the opposite end of said front wall, said gussets being disposed between said folded over end portions and the adjacent portions of said wall member.

10. In a wallet, billfold or the like, a compartment having a wall member, a sheet of material adhesively secured to said wall member and having a surface of heat-sealable material and folded over end portions provided with slits, respectively, a pocket member having a front wall and end portions projecting through said slits for attachment to said wall member, said folded over end portions being heat-sealed to said sheet of material with said pocket member end portions disposed therebetween for securing the latter to said wall member, said pocket mem-

ber having integral gussets at the opposite ends of said front wall, said gussets being disposed between said folded over end portions and the adjacent portions of said wall member.

5 11. In a wallet, billfold or the like, a compartment having a wall member having a surface of heat-sealable material and having folded over end portions provided with slits, respectively, a pocket member having a front wall and end portions projecting through said slits for attachment of said pocket member to said wall member, and means heat-sealed to said heat-sealable material for securing said folded over end portions in said folded over condition and thereby securing said end portions of said pocket member to said wall member, said pocket member having integral gussets at the opposite ends of said front wall, said gussets being disposed between said folded over end portions and the adjacent portions of said wall member.

20 12. In a wallet, billfold or the like, a compartment having a wall member, a sheet of material adhesively secured to said wall member and having a surface of heat-sealable material and folded over end portions provided with slits, respectively, a pocket member having a front wall and end portions projecting through said slits for attachment of said pocket member to said wall member, said folded over end portions being heat-sealed to said sheet of material with said pocket member end portions disposed therebetween for securing the latter to said wall member, said pocket member having integral gussets at the opposite ends of said front wall, said gussets being disposed between said folded over end portions and the adjacent portions of said wall member, and a wall member in overlapping laminated relation with said sheet of material and heat-sealed to said heat-sealable surface thereof.
